UNITED STATES PATENT OFFICE.

WILLIAM H. FAY, OF CAMDEN, NEW JERSEY.

ROOFING.

SPECIFICATION forming part of Letters Patent No. 362,732, dated May 10, 1887.

Application filed November 19, 1886. Serial No. 219,397. (No model.)

To all whom it may concern:

Be it known that I, WILLIAM H. FAY, a citizen of the United States, residing in the city and county of Camden, State of New Jersey, have invented a new and useful Improvement 5 in Roofing, which improvement is fully set forth in the following specification and accompanying drawings, in which—

Figure 1 represents a top or plan view of 10 roofing embodying my invention. Fig. 2 represents a section in line *x x*, Fig. 1.

Similar letters of reference indicate corresponding parts in the two figures.

My invention consists of a roofing formed of 15 sheets which are secured in position by clips, whereby the same is water and air tight, easily made, and of light and inexpensive nature.

Referring to the drawings, A represents the covering-board or top portion of a roof, the 20 same being of usual construction.

B represents a sheet of roofing-paper or other suitable material, which is bent around the lower end of the board A and placed on the top thereof, as at *a*, after which it is 25 doubled on itself, as at *b*.

C represents a metallic clip of angular form, the same being nailed to the doubled material *b*, the nails employed being driven into the board A. The sheet is folded or bent upwardly over the clip C and laid on the board, 30 its upper end being doubled, as at C', and the end of another sheet of roofing material is inserted in the doubled or folded end C'. A clip, C, is placed on the doubled or folded material at C' and nailed thereto, the nails entering the board. The second sheet is now bent upwardly over the clip and continued upwardly, and the operations may be repeated 35 until the roof is completely covered.

If desired, the sheet, if sufficiently long, may 40 be continued from bottom to top of the roof, and doubled and folded at intervals, and secured thereat to the board by clips C, firmly

connecting the sheet with the board and preventing the same from being raised by the 45 force of the wind.

It will be seen that the roofing material, as doubled or folded and secured, is reliably retained in position and provides a water and air tight roof, the same being light, inexpensive, and durable.

The clips C are concealed by the folded sheet, whereby rusting of the same and of the fastening nails or tacks is avoided. The limbs of the clips in contact with the board rest firmly 55 against the same or are driven thereinto, whereby they hold the doubled or folded portions of the sheet tightly on the board, and are prevented from shifting should the sheet be forcibly struck by the wind, so that the sheet 60 is reliably retained in place on such occasion.

The roofing sheets may be painted or otherwise coated or covered in any suitable manner.

Having thus described my invention, what 65 I claim as new, and desire to secure by Letters Patent, is—

1. A sheet of roofing material having its ends folded on the board or top of the roof and secured by clips which are covered by 70 the continuation of said roofing material, substantially as described.

2. A roofing-sheet folded at intervals, and clips secured to the same by nails driven into the board or top of the roof, substantially as 75 described.

3. A roofing-sheet folded at intervals, and clips secured to the folded or doubled portions and the board or top of the roof, said clips being of angular form, substantially as 80 described.

WILLIAM H. FAY.
